UNITED STATES PATENT OFFICE

PERCIVAL S. TICE, OF CHICAGO, ILLINOIS, ASSIGNOR TO STEWART-WARNER CORPORATION, OF CHICAGO, ILLINOIS, A CORPORATION OF VIRGINIA

CARBURETOR

Application filed February 16, 1927, Serial No. 168,529. Renewed May 1, 1930.

The purpose of this invention is to provide a carburetor for an internal combustion engine adapted to deliver fuel to the fuel mixture conduit under pressure suitable to the running conditions of the engine, unaffected by the height of the fuel column anterior to the carburetor, and therefore unaffected by change in the height of said column resulting from consumption of fuel lowering the level of the fuel in the fuel supply tank or other fuel source. Incidental to this purpose it is the purpose of this invention to provide means in a carburetor for producing by engine suction a head of fuel in the duct by which the fuel is discharged in the fuel mixture conduit, for maintaining in periods of engine inaction and consequent interruption of suction, on the fuel in the fuel chamber from which the fuel mixture conduit derives the fuel element, a predetermined minimum pressure for holding seated a valve which controls flow of the fuel supply to the carburetor. The invention consists in the elements and features of construction for the purpose stated, shown and described as indicated in the claims.

The drawing is a vertical section of a carburetor embodying this invention, axial with respect to the fuel mixture conduit and also with respect to the fuel duct therefrom to said conduit.

In the drawing the fuel source is indicated by a tank, A, which is represented as connected to the carburetor by flexible pipe, B, so that the tank may be shifted from a position below the carburetor to a position above, and vice-versa, as indicated by the showing of the tank in dotted line in the two positions. This, it will be understood, is merely to indicate that the level of the fuel source with respect to the carburetor does not affect the operation, and that such source may be at any suitable height above or below the carburetor without affecting the operativeness or the specific operation of the carburetor.

The carburetor comprises a fuel mixture conduit, 10, adapted for connection to the intake manifold of the engine as indicated by the attaching flange, 11, and having an air inlet as indicated at 12; a fuel chamber, 20;

a fuel duct, 30, leading from the fuel chamber, 20, through a nozzle, 31, extended for discharge upwardly within the fuel mixture conduit; a fuel flow-restricting device of the character commonly called a "metering plug" 55 interposed in the last mentioned duct; a balanced valve, 80, for controlling flow of fuel to the fuel chamber from the fuel source at whatever level; a flexible diaphragm, 50, forming a wall of the fuel chamber operatively connected with said balanced valve for holding the valve at seated or open position according to the position of said flexible wall determined by the pressures operating at opposite sides thereof as hereinafter explained. In the specific structure illustrated the fuel chamber, 20, has the movable wall consisting of a flexible diaphragm, constituting the bottom of the chamber; but it will be understood that the movable wall may constitute the whole or any part of the wall at any side of the chamber whether lateral or upper or lower. This diaphragm wall is held to the chamber body by being bound at its margin between the surface of the chamber body marginal with respect to the chamber cavity and the corresponding marginal area of the bottom cap, 25, which is bolted to the chamber body, clamping the diaphragm between said marginal areas as seen 70 in the drawing. The cap, 25, has at its center an apertured and interiorly threaded boss, 25^a, into which there is screwed an adjustable plug, 25^b, between which and the diaphragm there is interposed a compression 80 coil spring, 60, suitably centered on the end of the plug and on the central disk shoe, 61, of the diaphragm which is clamped between said shoe and a washer, 62, on the opposite side by an eye bolt, 63, and a nut, 64, formed for centering the compression spring as mentioned. The top wall of the chamber is bored through at 20^a, to receive at the inner end a bushing, 70, and counterbored at the opposite end to receive a bushing, 72. The bushing, 70, is inserted from the inside of the fuel chamber and has a valve seat, 71, at the inner end facing outwardly with respect to the chamber; and the bushing, 72, has a flexible diaphragm, 73, spanning its central aper- 100

ture which is equal in area to the port, 71^a, through the valve seat, 71. A port, 76, leading in from the side of the chamber body, intersects the bore, 20^a, between the two bushings, 78; and a valve, 80, guided in the bore, 20^a, as indicated by the guide ribs, 20^b, and seating at the seat, 71, is connected at the opposite end to the diaphragm, 73, and has an axial bore seen at 81, extending inward from its seated end, at the upper end of which axial bore there is pivotally connected a link, 83, extending from said pivotal connection down through the axial bore, 81, and through the valve seat into the chamber, and pivotally connected at its lower end to the eye bolt, 63, at the center of the diaphragm, 50.

The parts described are dimensioned for positioning the diaphragm, 50, at the seated position of the valve, 80, substantially without deflection either way from the plane in which it is clamped to the chamber wall; and the adjustable screw plug, 25^a, is adjusted to cause the pressure of the spring at said seated position of the valve to substantially balance the forces tending to depress the diaphragm from its normal position, said forces including, when the chamber is arranged as shown with the diaphragm horizontal, the weight of the diaphragm and the washers between which it is clamped, and the weight of the liquid contents of the chamber filled to a predetermined level as hereinafter described.

The operation of the construction above described is as follows:

All the parts being in normal position, the valve, 80, being seated and pressed upon its seat by its own weight, and that of the connected parts so as to require only a predetermined slight lowering of the pressure in the chamber to cause the diaphragm, 50, to operate for opening the valve, upon the starting of the engine, the engine suction producing such lowering pressure in the chamber, and the valve being opened, the fuel will flow in and fill the chamber at once if the level of the fuel at the fuel source is above the level of the port controlled by the valve; and as soon as the engine suction becomes sufficient to lift the fuel from a lower level, if it is below the port level. The fuel entering the chamber and eventually filling it to the height of the port in the metering plug will be drawn by the suction through that port and fill the stand pipe nozzle, 31, from whose upper discharge end the fuel will be taken with the indrawn air through the fuel mixture conduit to the engine.

Under any given running conditions causing the engine suction to produce a given depression at the discharge of the stand pipe nozzle, the valve opening will be such as to permit a rate of fuel flow just sufficient to maintain the rate of flow through the metering plug which that degree of suction and resulting depression at the nozzle discharge

is capable of producing. And however widely the valve may have been opened in response to the suction operating on the diaphragm before the chamber and the stand pipe nozzle became filled with liquid, after they are thus filled the valve will settle to a position affording just adequate supply for the flow capacity of the port in the metering plug under the stated engine suction; because if the fuel enters faster past the valve than it can be drawn by the stated suction through the metering plug, the degree of vacuum in the chamber which operates to open the valve will fall, and atmospheric pressure on the area of the valve-balancing diaphragm and the weight of the accumulated fuel will close the valve until the flow of fuel past it no longer exceeds the flow capacity from the metering port under the given suction; and if the flow past the valve is less than the flow capacity of the metering port, the vacuum in the chamber will increase,—the depression becoming greater,—causing the diaphragm to operate for opening the valve more widely until the fuel flow past it equals the flow capacity of the port in the metering plug. And in such operation, (which, in fact, will not consist of back and forth valve and diaphragm movement, except to an invisible extent,) the height of the liquid column from which the fuel supply is derived past the valve, will have no effect upon the degree of pressure existing in the chamber, because as to the valve itself, the pressure of that column is balanced, acting on the area of the valve for closing, and upon the equal area of the diaphragm, 80, for opening. And as to the pressure which is communicated through the valve opening to the chamber and to the liquid therein, any increase of that pressure acts on the diaphragm to close it and thereby reduce the access of fuel which causes outflow through the metering port in response to engine suction for lowering the pressure in the chamber. And these theoretically back-and-forth changes will be of infinitesimal duration, so that practically there will be no change of pressure in the chamber under any given suction.

The adjustment of the spring, 60, for causing the valve to be normally seated so as to be opened upon a predetermined minimum depression in the chamber, is taken into account in connection with the pressure which will be exerted by the fuel column in the stand pipe nozzle when the structure is in operation and in intervals of operation after once started; and that pressure operating on the diaphragm for closing the valve becomes a measure of the lowest degree of engine suction that will cause the valve to remain open for admission of fuel after first starting from the condition of an empty chamber.

I claim:—

1. A carburetor for internal combustion engines comprising in combination with a fuel mixture conduit adapted for discharge connection into the intake manifold of the engine and having an air inlet; a fuel chamber having connection with a fuel source and means for maintaining predetermined pressure on the liquid in said chamber, a fuel delivery duct extending from said chamber for discharge in the fuel mixture conduit at a substantial distance above the fuel level of the fuel chamber; the means for maintaining the predetermined pressure in the fuel chamber consisting of a conduit for fuel flow from the source to said chamber, a valve in said conduit and means by which the pressure of the fuel from the source is balanced in the opposite directions for seating and unseating the valve, said chamber having a movable wall for expanding and reducing the chamber capacity, said wall being operatively connected with said balanced valve for closing it by the chamber-expanding movement of said wall, and opening it more or less by its chamber-reducing movement, yielding means acting on said moving wall for chamber-reducing movement, and means for adjusting said yielding means in predetermined relation to the pressure of a liquid column in the fuel duct leading from said chamber to the discharge of said duct in the fuel mixture conduit.

2. A carburetor for internal combustion engines comprising in combination with a fuel mixture conduit adapted for discharge connection into the intake manifold of the engine and having an air inlet; a fuel chamber having connection with the fuel source, and means for maintaining a predetermined pressure on the fuel in such chamber, a fuel delivery duct from said chamber extending for discharge in the fuel mixture conduit at a substantial distance above the fuel level of said fuel chamber; a calibrating fuel flow restriction interposed in said duct; the means for maintaining said predetermined pressure in the chamber consisting of a conduit for flow of fuel from the source to said fuel chamber; a shut-off valve in said conduit; means for rendering the rate of flow through said conduit independent of the level of the fuel source; said chamber having a movable wall by whose movement the chamber is expanded and reduced, said movable part being exteriorly exposed to atmospheric pressure for forcing it inward to reduce the chamber capacity; additional means yieldingly actuating said wall in the direction for reducing the chamber capacity, and means for adjusting said yielding means in predetermined relation to the pressure of the liquid column in the fuel duct leading from said chamber for discharge in the fuel mixture conduit, and operating connections from said movable wall

for seating the shut-off valve by the chamber-expanding movement of said wall.

3. A carburetor for internal combustion engines comprising in combination with a fuel mixture conduit adapted for discharge connection into the intake manifold of the engine and having an air inlet, a fuel chamber having connection with a fuel source, and means for maintaining predetermined pressure on the liquid in said chamber; a fuel delivery duct extending from said chamber for discharge in the fuel mixture conduit; a conduit for fuel flow from the source to said chamber; a valve in said conduit, and means by which the pressure of the fuel from the fuel source operates on the valve equally in opposite directions; said chamber having a movable wall, said wall being positively connected with said valve for movement both in seating and unseating direction; and a spring reacting on said moving wall for valve-opening movement.

4. The construction defined in claim 3 having the fuel delivery duct which discharges in the fuel mixture conduit extending upwardly for holding a liquid column to react by hydrostatic pressure on the contents of the fuel chamber, the spring being arranged for reacting on the movable wall of the fuel chamber correspondingly to the degree of said hydrostatic pressure.

5. A carburetor for internal combustion engines comprising in combination with a fuel mixture conduit adapted for discharge connection into the intake manifold of the engine and having an air inlet; a fuel chamber having fuel flow connection with a fuel source; a fuel delivery duct from the fuel chamber discharging in the fuel mixture conduit, said duct being arranged to carry a fuel column for reacting by hydrostatic pressure on the content of the fuel chamber; a shut-off valve in the connection of the fuel chamber with the fuel source; means for rendering the rate of flow past said valve independent of the level of the fuel source, the fuel chamber having a movable wall member exteriorly exposed to atmospheric pressure forcing it inwardly; additional resilient means for exerting pressure on said wall member in chamber-reducing direction arranged to exert said pressure in a degree corresponding to the hydrostatic pressure of said fuel column, and operating connections from the movable wall for seating the shut-off valve by the chamber-enlarging movement of said wall member.

6. A carburetor for internal combustion engines comprising in combination with a fuel mixture conduit adapted for discharge connection with the intake manifold of the engine, and having an air inlet; a fuel chamber having connection with a fuel source; a fuel delivery duct from said chamber extending for discharge in the fuel mixture conduit, said duct being arranged to carry a

fuel column for reacting by hydrostatic pressure on the content of the fuel chamber; a conduit for flow of fuel from the source to said fuel chamber; means for rendering the rate of flow through said conduit independent of the level of the fuel source consisting of a shut-off valve in the conduit and means for balancing the fuel pressure on the valve in the opposite of the valve seating direction, said chamber having a movable wall member, said wall member and said pressure-balancing means being exposed exteriorly of said chamber and said conduit respectively to equal fluid pressures; additional means actuating said wall member inwardly, said additional means arranged to operate correspondingly to the hydrostatic pressure of the fuel column in the fuel delivery duct, and operating connections from said movable wall member for seating the shut-off valve by the chamber-enlarging movement of said wall member.

In testimony whereof, I have hereunto set my hand at Chicago, Illinois, this 11th day of February, 1927.
